DESIGN FOR A WOMAN'S BIFURCATED GARMENT

Felix A. Lacks, Pelham Manor, N. Y.

Application March 8, 1934, Serial No. 50,978

Term of patent 14 years

To all whom it may concern:

Be it known that I, FELIX A. LACKS, a citizen of the United States, residing in Pelham Manor, county of Westchester, State of New York, have invented a new, original, and ornamental Design for Women's Bifurcated Garment, of which the following is a specification, reference being had to the accompanying drawing forming a part thereof, in which:

The figure is a perspective view of the garment showing the new design.

I claim:

The ornamental design for woman's bifurcated garment substantially as shown.

FELIX A. LACKS.
